GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

FUSE-PLUG.

1,078,472.

Specification of Letters Patent. Patented Nov. 11, 1913.

Application filed November 25, 1912. Serial No. 733,513.

To all whom it may concern:

Be it known that I, GEORGE B. THOMAS, a citizen of the United States of America, and residing at Bridgeport, in the county of Fairfield and State of Connecticut, have invented a certain new and Improved Fuse-Plug, of which the following is a specification.

The present invention relates to fuse 10 plugs particularly of the screw plug type, and the object of my invention is to provide an improved cap and fastening device therefor.

In the accompanying illustrative embodiment of my invention, Figure 1 is a side elevation of a fuse plug in which my invention is embodied; Fig. 2 is a detached elevation of the plug body and cap in position for assembly; and Fig. 3 is a plan view 20 of the plug.

It is the common practice in fastening caps on fuse plugs to press a portion of the depending peripheral flange of the cap into a "staking" recess in the body of the porcelain in order to prevent the rotation of the cap on the plug. In order to accomplish this 25 it is necessary for the plug to be exactly positioned in the die so that the "staking" recess shall accurately register with the 30 staking plunger which serves to press the metal of the flange into the recess. Carelessness in thus positioning the plug body in the die results in breakage of the plug during manufacture, as well as injury to 35 the male die. The present invention obviates the necessity for "staking" the cap, and thus not only eliminates this step in the cost of manufacture, but also avoids the breakage expense hitherto incident thereto.

In the embodiment of my invention here- 40 with illustrated, the body 5 of the plug is formed from a single piece of porcelain, of which the upper portion is outwardly shouldered at 6 to form a head. Against the latter abuts the upper edge of the usual shell 45 7 which is screwed on the threads 8 formed on the insulating body of the plug. A peripheral flange 9 is formed on the head above the shoulder 6 and longitudinal ribs 50 10 spaced at intervals around the head extend upward from this flange to the upper edge of the head of the plug.

The metallic cap 11, centrally apertured as usual at 12 to afford a sight aperture, is 55 provided with a depending peripheral flange

13 crimped along its upper portion to form a series of channels 14 on its inner face so arranged and proportioned with relation to the ribs 10 that the latter freely enter the channels in whatever relative rotary position the cap may be fitted on the plug head. The lower portion of the flange is plain and extends beyond the peripheral flange 9 so that it may be spun under the latter, as shown in Fig. 1 to prevent the endwise separation of the cap from the body of the plug. 60

It will be readily understood that the engagement between the ribs 10 and the channels 14 prevents the relative rotary displacement of the cap with relation to the head of the plug, so that the plug may be screwed firmly home in its receptacle while gripping merely the cap. The crimping of the periphery of the flange also affords an excellent finger grip so that the plug may be turned without danger of the fingers slipping. The assembly of the cap on the plug body is greatly facilitated since it may be fitted thereon in substantially any position 70 rotarily, and the single operation thereafter necessary to secure it against endwise separation from the plug is merely the spinning of the lower edge of the flange 13 beneath the peripheral flange 9 on the plug body, an operation which can be accomplished without danger of injury to the 75 plug.

I claim as my invention:—

1. A fuse plug, comprising a head portion provided with longitudinal ribs and a cap with a depending flange having longitudinal channels to engage said ribs whereby relative rotary displacement of said cap and head is prevented, together with means for preventing endwise separation of said parts. 90

2. A fuse plug, comprising a head portion provided with longitudinal ribs on its external periphery and a cap with a depending peripheral flange having longitudinal channels to engage said ribs whereby relative rotary displacement of said cap and head is prevented, together with means for preventing endwise separation of said parts. 100

3. A fuse plug comprising a head portion provided with peripheral flange and longitudinal ribs extending upward therefrom, in combination with a cap having a depending peripheral flange having longitudinal channels in its upper portion to engage said ribs whereby relative rotary displacement 105

110

of said parts is prevented, the lower portion of said flange being turned under said peripheral flange on the head to prevent endwise separation of the parts, substantially as described.

4. In a fuse plug of the type described, a cap having a peripheral flange crimped in its upper portion to form a series of channels for the purpose described and a plain 10 cylindrical lower portion, the edge of which is adapted to be turned inwardly, substantially as described.

5. In a fuse plug of the type described, a head portion having a peripheral flange and ribs extending upwardly therefrom for 15 the purpose described.

In testimony whereof I have signed my name to this specification, in the presence of two subscribing witnesses.

GEORGE B. THOMAS.
